Jack G. Josel

UNITED STATES PATENT OFFICE

171,895

CANDELABRA

Jack G. Josel, Long Beach, Calif.

Application July 14, 1953, Serial No. 25,949

Term of patent 14 years

(Cl. D43—2)

To all whom it may concern:

Be it known that I, Jack G. Josel, a citizen of the United States, residing at 2924 East Second Street, Long Beach, in the county of Los Angeles and State of California, have invented a new, original, and ornamental Design for a Candelabra, of which the following is a specification, reference being had to the accompanying drawing, forming a part hereof.

Fig. 1 is a front elevational view of a candelabra, showing my new design; and Fig. 2 is a top plan view thereof.

I claim:

The ornamental design for a candelabra, as shown.
